BALL PITCHING DEVICE

Henry G. Atwell, Lake Villa, Ill.

Application January 24, 1948, Serial No. 4,130

7 Claims. (Cl. 124—4)

1

This invention relates to a ball pitching device, and is in the nature of an improvement on the ball catching and pitching machine disclosed in my prior Patent No. 2,082,818, dated June 8, 1937.

One of the objects of the present invention is to provide enclosing means for the connection between the foot treadle means and ball throwing member of the device, whereby said connection is concealed and there is no likelihood that it will become tangled when the device is knocked down for storage or shipment.

Another object is to provide a connection between the treadle means and ball throwing member in the form of a jointed metal ribbon, whereby it may be folded alongside the base sections when the latter are taken apart for the purpose of storage and shipment.

Another object is to provide simple means to attach the metal ribbon to the treadle means when setting the device up for use.

Another object is to provide a base in the form of telescopic tube sections, whereby its length may be considerably reduced for storage and shipment and whereby the connection between the treadle means and ball throwing member may be enclosed.

With these and other objects and advantages in view, this invention consists in the several novel features hereinafter fully set forth and claimed.

The invention is clearly illustrated in the drawings accompanying this specification in which:

Fig. 1 is a perspective view, partly broken away, of a ball pitching and catching device embodying a simple form of the present invention;

Fig. 2 is a detail fragmental view, partly in side elevation and partly in vertical longitudinal section, taken on the line 2—2 of Fig. 1;

Fig. 3 is a detail fragmental section through the ball catching and throwing elements, taken on the line 3—3 of Fig. 1;

Fig. 4 is a view partly in side elevation and partly in longitudinal section through a fragment of the foremost tube section of the telescopic base, the line of section being taken at 4—4 in Fig. 1;

Fig. 5 is a plan of the device showing the same in knocked down condition;

Fig. 6 is a view partly in side elevation and partly in vertical longitudinal section taken on the line 3—3 of Fig. 1 but showing the ball catching element in its down position; and

Fig. 7 is a detail vertical cross section taken on the line 7—7 of Fig. 6.

2

Referring to said drawings, which are merely illustrative of one embodiment of the invention, the reference character 10 designates a base, as a whole, composed of several tube sections 11, 12 and 13 with their adjacent end portions partially telescoped into each other (see Fig. 2). Pin and slot connections 14, 15 are provided upon the adjacent ends of the tube sections for preventing relative rotation between them.

To the lower sides of the endmost tube sections at their free ends, bolted, riveted, welded or otherwise secured thereto, are elongated plates 16, 17 which extend crosswise of the base and serve as steadyng members for holding the parts 15 of the device upright. The plate 16 may be regarded as the front steadyng member and the plate 17 as the rear steadyng member.

On the front steadyng member 16 is rotatably mounted treadle means 18 having a shaft 20 journaled in a bearing bracket 20 welded or otherwise secured to the front steadyng member, said shaft being also journaled in a bearing aperture in the tube section 11. The treadle may be in the form of a small rectangular L-shaped plate 18a secured to the shaft 19 as by a screw or otherwise, as desired. To the shaft 19 within the tube section 11 is secured an arm 21 having a slot 22 in its upper end in which the hereinafter described connection with the ball throwing member is removably secured as by a link 35 which engages a side of the arm 21.

Pivottally mounted in the rearmost tube section 13 as by a pin 24 is a ball throwing member 25. This ball throwing member has an actuating arm 26 having one bent end which extends through a slot 27 in said rearmost tube section 13 to the interior thereof where its inner end is pivoted to the tube section by the pin 24. To the other end of the actuating arm 26 is riveted, bolted, welded or otherwise secured thereto a trough-like ball receiver 28 with a ball retaining member 28a at one end thereof which prevents the hereinafter mentioned ball from rolling out of the ball receiver 28. Connecting the actuating arm 26 and arm 21 of the treadle means is a connection 29 desirably composed of sections 30, 31 and 32 of metallic ribbon or strips pivottally connected together as by rivets 33 to permit the sections to be extended for use or folded together for the purpose of storage and shipment. Each section may terminate approximately at the adjacent telescopic ends of the tube sections, whereby when folded, the several sections will occupy a length approximately 55 equal to the length of one of the tube sections,

One end of the connection 29 is connected to the actuating arm 26 by a rivet 34 and the other end is connected to the treadle arm 21 by a link 35. The connection 29 is removably secured to the treadle arm 21 to permit the base to be knocked down. A coiled tension spring 36 fastened to a pin 37 secured in the tube section 13 with the other end of the spring fastened to the connection 29 serves to swing the ball thrower down into position for receiving a ball from the ball catcher.

Pivotedly mounted on the pin 37 is a stand 39 having two upright side walls 40 connected by an end wall 41 having a hole 42 therein adjacent its lower end, through which a ball may pass from the rear side of the end wall to the ball throwing member. The stand may be pivotally connected with the pin 37 at places adjacent the forward edges of the side walls 40 of the stand to enable it to stand upright. The greater amount of the weight of the stand being to the rear of its pivot point, it maintains the stand in upright position when raised into upright position.

Secured to the side walls of the stand is a ball catching element, designated generally by the reference character 44. Said ball catching element comprises a rearwardly bowed fabric sheet of material 45, which has a downwardly projecting portion 46 which extends down behind the end wall 41 of the stand and together with said end wall forms a channel through which a ball, caught by the bowed portion of the sheet of material may gravitate to the bottom of the channel. An inclined wall 47 secured to the end wall 41 below the opening 42 therein closes the bottom of the channel and directs a ball which falls upon the inclined wall, through the opening in the end wall where it lodges upon the ball throwing member. The edge of the bowed portion of the ball catching element is generally half round and below the half round part the side edges thereof are straight. The sheet of material is formed with a hem 48 along its edges, through which extends a flexible metal strip 49 having a half round part 50 which terminates in upright legs 51 that are secured to the side walls of the stand by screws 52.

The game is played with a ball, preferably a rubber ball 53 (see Fig. 3). The player stands adjacent the treadle means and throws the ball into the ball catching element and it gravitates down to the inclined wall 47 where it is deflected upon the ball throwing member 25. The player then depresses the treadle 18a with more or less force thereby drawing the connection 29 toward him and swinging up the ball throwing member 25, which projects the ball in the direction of the player who endeavors to catch it during its flight.

To knock down the device, the link 35 is disconnected from the treadle arm 21 and the tube sections are detached from each other and laid side by side as seen in Fig. 5. The connection strips 30, 31 and 32 are folded upon each other as seen in Fig. 5 and laid among the tube sections. The ball catching element is then swung down upon its pivot 37. In this knocked down condition the entire device can be contained in a carton 54 (see Fig. 5) of the dimensions shown therein, the half round part of the flexible strip 50 being collapsed somewhat as seen at 50a to enable it to be placed within the carton of the dimensions shown.

In assembling the device, the connection strips are inserted through the tube sections 11 and 12 and the tube sections telescoped together. The

strip section 30 may be engaged with the treadle arm 21 by means of a button-hook or the like (not shown) which may be introduced through the open end of the tube section 11 and engaged with the link 35, whereby the end of the strip 30 may be let into the slot 22 in the top of the treadle arm 21. The link will be drawn into engagement with the treadle arm by the spring 36.

Having thus described my invention, it is obvious that various immaterial modifications may be made in the same without departing from the spirit of my invention; hence, I do not wish to be understood as limiting myself to the exact form, construction, arrangement and combination of parts herein shown and described or uses mentioned.

What I claim as new and desire to secure by Letters Patent is:

1. In a ball pitching device, a tubular base, treadle means mounted on one end of the base, a ball throwing member pivotally mounted at the other end of the base and having a bent arm extending into the hollow of the base, and a flat, jointed strip connecting said treadle means and ball throwing member and extending through said tubular base, said strip having a pivotal joint adjacent each juncture of adjoining tube sections.
2. In a ball pitching device having treadle means, a ball throwing member and a jointed strip connection therebetween, a base composed of several telescopic tube sections in which the connection is contained, and a pair of substantially flat, steadyng members one at each end of the base and rigidly secured to the latter, said steadyng members each extending tangentially outward from the bottom of the tubular base at both sides of the latter, with both members lying substantially in a common plane.
3. In a ball pitching device, a base comprising several telescopic tube sections and steadyng means at the ends of the base, treadle means mounted at one end of the base, a ball throwing member mounted at the other end of the base, and a flat, jointed strip connecting the treadle means and ball throwing member and extending through said tube sections, said strip having a pivotal joint adjacent each juncture of adjoining tube sections, said strip being detachably secured to the treadle means and permanently attached to the ball throwing member.
4. In a ball pitching device, a base comprising several telescopic tube sections and steadyng means at each end, treadle means at one end of the base having a shaft rotatably mounted upon the base, a notched arm secured to the shaft, a ball throwing member pivotally supported adjacent the other end of said base, a jointed strip secured to said ball throwing member, with its other end extending through the notch in the arm, and having a link secured on its end bearing against said arm.
5. In a ball pitching device, a base comprising several telescopic tube sections and steadyng means at the ends of the base, treadle means mounted at one end of the base, a ball throwing member mounted at the other end of the base, a flat, jointed strip connecting the treadle means and ball throwing member and extending through said tube sections, said strip having a pivotal joint adjacent each juncture of adjoining tube sections, said jointed strip having a link detachably secured to the treadle means and permanently attached to the ball throwing member, and a coiled tension spring attached to the

ball throwing member for swinging the same down.

6. In a ball pitching device, a base comprising several telescopic tube sections and steadyng means at each end, treadle means at one end of the base having a shaft rotatably mounted upon the base, a notched arm secured to the shaft, a ball throwing member pivotally supported adjacent the other end of said base, a jointed strip secured to said ball throwing member, with its other end extending through the notch in the arm and having a link secured on its end bearing against said arm, and a coiled tension spring attached to the ball throwing member for swinging the same down.

7. In a ball pitching device, a base having telescopic tube sections, one end tube section having a slot in its wall, a ball throwing member having an actuating arm extending through said slot with its end pivotally mounted in said slotted tube section, a coiled tension spring connecting said arm to a stationary pin mounted in said tube

section, and a jointed metal strip extending through said tube sections and connecting the treadle means with the actuating arm of the ball throwing member, said strip having a pivotal joint adjacent each juncture of adjoining tube sections.
